UNITED STATES PATENT OFFICE

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN

AIR GUN

Application filed December 19, 1927. Serial No. 241,138.

The invention relates to air guns of that type commonly known as pump guns in which the compression of the spring is effected by the reciprocation of a handle longitudinally of the barrel. The invention more particularly refers to an improvement in the mechanism actuated by the handle for moving the plunger to firing position and compressing the spring and one of the objects of the invention is to provide a mechanism which upon movement of the handle in a rearward direction moves the plunger to firing position and upon movement of the handle in a forward direction compresses the spring. Another object is to provide a mechanism which is designed to compress the spring by relatively easy movement of the handle. Further objects of the invention reside in the novel features of construction and combinations and arrangements of parts as more fully hereinafter set forth.

In the drawings:

Figure 1 is a side elevation of an air gun embodying my invention;

Figures 2, 3 and 4 are cross sectional views showing the parts in different positions of adjustment;

Figure 5 is a sectional view of the plunger assembly;

Figures 6, 7, 8, 9 and 10 are cross sections, respectively, on the lines 6—6, 7—7, 8—8, 9—9 and 10—10 of Figure 4.

The air gun, as shown, has the stock 1, the frame 2, the false barrel 3 and the true barrel 4 and plunger abutment 5 within the false barrel. The frame is struck up from sheet metal to form parallel side flanges 6 and a rounded upper portion 7, the side flanges being apertured and having the in-turned flanges 8 surrounding the aperture to form a trigger guard. The false barrel 3 has its rear end portion 9 telescopically engaging within the rounded upper portion of the frame and is secured to this frame by means of the clip 10 and the screw 11, the clip being fixed upon the false barrel and having depending ears 12 embracing forwardly projecting ears 13 upon the side flanges 6 and the screw extending through these ears below the false barrel. The rear

end portion 9 of the false barrel has the bottom slot 14 which extends longitudinally thereof. 15 is the handle which is reciprocable longitudinally of the false barrel and is located therebelow and 16 is a guide rod for the handle extending longitudinally below the false barrel and secured at its rear end by means of the screw 11 and at its front end by means of the clip 17 and screw 18, the clip embracing the false barrel and having a depending U-shaped portion for engagement with the guide rod and the screw extending through this U-shaped portion and engaging in a notch 19 formed in the upper edge of the guide rod.

20 is a plunger slidable within the false barrel in rear of the plunger abutment 5 and 21 is a plunger shank which is rigidly secured to the plunger and extends rearwardly therefrom. This shank is preferably formed of sheet metal and has the front tubular portion 22 and the spaced side portions 23 extending rearwardly from the tubular portion, the upper edges of the side portions at their rear ends being connected by the rounded top 24 and the rear ends of the side portions being connected by the transverse flange 25. The rounded top forms the shoulder 26 while the rear flange forms the shoulder 27 engageable with the sear 28 forming part of the trigger mechanism 29. 30 is a coil spring encircling the shank 21 and abutting the plunger 20 and adapted when compressed to move the plunger toward the plunger abutment.

The actuating mechanism for moving the plunger to firing position, at which time the shoulder 27 upon the plunger shank is in locking engagement with the sear 28 and for compressing the coil spring 30, comprises the front and rear toggle levers 31 and 32, respectively, the link 33 and the actuating abutment 34. These parts are preferably formed of sheet metal, the toggle levers being U-shaped with both toggle levers adapted to embrace the guide rod 16, the side flanges of the rear toggle lever being cut away at 35 to receive the screw 11 when the handle is in its forwardmost position. The front end of the front toggle

lever is pivotally connected to the handle while its rear end is pivotally connected to the front end of the rear toggle lever, the rear end of the latter being upwardly offset and being pivotally connected to the frame in advance of the trigger guard. This rear toggle lever extends between the side flanges 6 of the frame and has the upwardly extending ears 36 extending from its upwardly offset rear end portion in advance of the pivot connecting the rear toggle lever to the frame. The link 33 has its rear end extending between and pivotally connected to the ears 36 and its front end extending between and pivotally connected to the side flanges 37 of the actuating abutment 34, the latter being preferably formed of sheet metal and having an inverted U-shape. This abutment extends between the spaced sides 23 of the plunger shank and for holding the abutment from accidental disengagement the rear ends of its side flanges are formed with the transverse ears 38 which extend outwardly over the spaced side portions 23 and the front ends of the side flanges are formed with the extensions 39 which engage in the coil spring 30, the rear convolution of this coil spring abutting the shoulders 40 formed upon the side flanges at the opposite edges of the extensions.

With this arrangement, it will be seen that the rearward movement of the handle 15 first breaks the toggle levers 31 and 32 forcing their connected ends downwardly. Then through the rear toggle lever and the link 33 pulls the actuating abutment 34 rearwardly, which through the ears 38 and the shoulder 26 forces the plunger abutment and plunger rearwardly to firing position, at which time the shoulder 27 engages the sear 28. Then upon forward movement of the handle 15 the toggle levers are progressively straightened out and through the rear toggle lever and the link the actuating abutment is forced forwardly to compress the coil spring 30. By reason of the link 33 being connected to the rear toggle lever 32, which latter is connected to the front toggle lever 31, the power exerted by the actuating mechanism is progressively increased as the resistance of the coil spring to compression is increased, thereby rendering the forward movement of the handle relatively easy. Furthermore, by reason of the link 33 being connected to the upwardly offset ears 36, the pivot between the link and ears is located past center or upwardly beyond the line between the pivot connecting the rear toggle lever 32 to the frame 6 and the pivot connecting the link 33 to the actuating abutment 34, so that the coil spring 30 functions to hold the toggle levers 31 and 32 in place when the handle is in its forwardmost position.

65 What I claim as my invention is:

1. In an air gun, the combination with a barrel, of a plunger therewithin, a spring for moving said plunger, in one direction, a handle reciprocable longitudinally of said barrel, a toggle lever pivotally connected to said handle, a second pivotal toggle lever pivotally connected to said first mentioned toggle lever, a link pivotally connected to said second toggle lever intermediate its first mentioned pivots, and an actuating abutment pivotally connected to said link for moving said plunger to firing position and compressing said spring upon movement of said handle in opposite directions respectively. 70

2. In an air gun, the combination with a frame and a barrel, of a plunger within said barrel, a spring for moving said plunger in a forward direction, a handle reciprocable longitudinally of said barrel, a front toggle lever pivotally connected to said handle, a rear toggle lever pivotally connected to said front toggle lever and to said frame, a forwardly extending link pivotally connected to said rear toggle lever intermediate its first mentioned pivots, and an actuating abutment pivotally connected to the front end of said link for moving said plunger rearwardly to firing position and compressing said spring respectively upon movement of said handle in opposite directions. 80

3. In an air gun, the combination with a barrel, of a plunger therewithin, a spring for moving said plunger in one direction, a handle reciprocable longitudinally of said barrel, and means actuated by said handle for compressing said spring, including toggle levers held adjacent to said barrel by said spring when the handle is in its forwardmost position. 90

4. In an air gun, the combination with a barrel, of a plunger therewithin, a spring for moving said plunger in one direction, a handle reciprocable longitudinally of said barrel, an actuating abutment for said spring, a toggle lever pivotally connected to said handle, a second pivotal toggle lever pivotally connected to said first mentioned toggle lever, and a link for moving said actuating abutment pivotally connected to said second toggle lever at a point such that when said toggle levers extend adjacent to said barrel said spring functions to normally hold said toggle levers in place. 100

5. In an air gun, the combination with a frame, and a barrel, of a plunger within said barrel, a spring for moving said plunger in a forward direction, a handle reciprocable longitudinally of said barrel, a front toggle lever pivotally connected to said handle, a rear toggle lever pivotally connected to said front toggle lever and to said frame and having an upwardly extending portion intermediate its pivots, and a forwardly extending link for actuating said spring, said 110

- link being pivotally connected to said upwardly extending portion.
- 6. In an air gun, the combination with a barrel, of a plunger therewithin, an abutment slidably mounted within said barrel, a link having one end connected to said abutment, means for actuating said abutment including toggle levers connected to the opposite end of said link and a spring for moving said plunger engageable with said abutment tending to urge the latter together with the link in a direction to yieldably hold the toggle levers adjacent to said barrel.
- 10 7. In an air gun, the combination with a barrel, of a plunger therewithin, a spring for moving said plunger in one direction, a handle movable in opposite directions, a toggle lever pivotally connected to said handle, a second toggle lever pivotally connected to said first mentioned toggle lever, an actuating abutment slidable within said barrel and engageable with the plunger and spring, and means establishing a connection between said second mentioned toggle lever and said abutment operable upon movement of the handle in opposite directions to respectively move said plunger to firing position and compress said spring.
- 15 8. In an air gun, the combination with a barrel, of a plunger therewithin, a spring for moving said plunger in one direction, a handle reciprocable longitudinally of said barrel, and means actuated by said handle for compressing said spring, including toggle levers held adjacent to said barrel by said spring in both the compressed and released position of the latter.
- 20 9. In an air gun, the combination with a barrel, of a plunger therewithin, a spring for moving said plunger in one direction, an actuating handle reciprocable longitudinally of the barrel, and means actuated by said handle for compressing said spring, including toggle levers held adjacent to said barrel by said spring in the compressed position of the latter.
- 25

In testimony whereof I affix my signature.
CHARLES F. LEFEVER.
